Patented June 18, 1918.

UNITED STATES PATENT OFFICE.

WILLIAM GENTRY SHELTON, OF NEW YORK, N. Y.

DRIVING MECHANISM.

1,269,752.

Specification of Letters Patent. Patented June 18, 1918.

Application filed April 10, 1916. Serial No. 90,051.

To all whom it may concern:

Be it known that I, WILLIAM GENTRY SHELTON, a citizen of the United States of America, residing in the borough of Manhattan, city, county, and State of New York, have invented certain new and useful Improvements in Driving Mechanism, of which the following is a specification.

The object of the invention is to provide a subsidiary electric motor for operating a driven part, particularly one which is repeatedly started and stopped at brief intervals, as for instance, the rotary portions of a sewing machine or talking machine, which are provided with driving mechanism for such rotary part and which part is capable of being started and stopped independently of its primary driving mechanism. In starting talking machines the record supporting platen is frequently given a forward impulse by hand to assist the spring in overcoming the inertia of the driven parts and on the completion of the reproduction of the record the platen is stopped either by a brake or by hand. The present improvement takes advantage of these various mechanisms, as well as of the governor for controlling the speed of rotation of the driven part, for instance, the talking machine platen. It also provides mechanism in the subsidiary motor whereby upon the starting of the driven part, the motor circuit is automatically closed, and upon the slowing down or stopping of such part, the motor circuit is opened.

The drawing accompanying and forming a part of this application is a view partly in elevation and partly in vertical section of a practicable embodiment of my invention as applied to a talking machine.

For the purpose of illustrating the invention a talking machine mechanism has been selected for the drawings. The table 1 of the frame work is shown carrying a horizontally disposed rotary supporting platen 2 for carrying and rotating the record 3, some suitable material such as felt 4 being interposed between the platen and the record. Two motor drivers are illustrated, the primary driver being in the form of a spring motor, and the subsidiary driver being in the form of an electric motor. Both of these motors are illustrated as secured to and carried by the table 1 of the frame. The platen is shown carried by a spindle disposed substantially in a vertical position and acting

as the axis or pivot about which the platen rotates.

The primary motor, in the present illustration a spring motor, acts upon the spindle and thereby rotates the platen. The spindle is shown provided with a worm 6 with which meshes a worm wheel 7. The spring is housed in a well known manner in a barrel 8 supported by a shaft 9. The ends 60 of the spring are of course connected respectively to the worm wheel 7 and a ratchet wheel 10 engaging an escapement dog 11 pivoted to the frame work of the machine. This dog and ratchet wheel escapement 65 constitutes a convenient form of clutch mechanism between the primary driver and the rotatable member, the platen in the illustration, whereby the latter may be operatively clutched to and driven by the former 70 or may run forward independently of such primary driver. The construction of the illustrated primary motor is such that when the spring is wound, it rotates the platen 75 forwardly in the proper direction, and 80 when the spring is unwound, the platen may be rotated forwardly in the same direction, this being permitted in the present illustration by the escapement mechanism above mentioned.

In the present showing the platen and spindle 5 are adapted to move together. A governor is provided for the platen and is adapted to control the speed of the same whether the rotative force is applied to the 85 platen through the spindle or is applied to the spindle through the platen. A well known form of ball governor is shown in the present illustration. This comprises a spindle 12 mounted in suitable bearings and 90 carrying a worm wheel 13 meshing with a worm wheel 14 fast on the platen spindle 5. The governor spindle has associated with it a plurality of spring members 15, each provided with a suitable weight or ball 16. 100 Spring members 15 are shown connected to a plate 17, which, upon the rotation of the platen 2 and the outward centrifugal movement of the balls will be drawn toward the left in the illustration, and upon excessive 105 rotation against a suitable braking device. The drawing shows the parts in the position of rest, and the friction member 18 of the brake in engagement with the governor disk 17. The friction member 18 is shown 110 carried by a lever 19 pivoted to the frame work and associated with actuating mecha-

nism 20 on the upper side of the table 1. In this form of governor, the brake lever is set either at the position of stop or any predetermined degree of speed and cooperates with the governor in assuring the proper control of the platen when under the rotative influence of driving mechanism, whether this is furnished by the primary motor, an example of which has just been described, 10 or by the subsidiary motor presently to be described.

From the foregoing description, it will be apparent that the rotative part, the platen in the present illustration, may be driven 15 forward independently of its primary motor, particularly when the spring is run down, but that such independent rotation is, nevertheless, controlled by the governor and the brake. In addition to the primary motor, a 20 subsidiary driver is illustrated in the form of an electric motor which may be held out of driving relation when the primary motor is to be employed, and which may also be brought into driving relation with such 25 platen and apply tractive force thereto and properly drive the record, the speed imparted to the record being controlled and governed by the governor associated with the primary driver mechanism.

80 The electric motor illustrated in the drawing is shown permanently attached to the table 1 of the frame work by means of a supporting bracket 25 secured in position by means of screws. The term "permanently connected" is used to indicate that this motor is built in with the machine and constitutes a part thereof, and when built in becomes an element of the permanent equipment.

Circumstances surrounding the use of each 40 particular instrument determine which motor will be the one which is customarily used and which will be held as a reserve in case the customarily employed motor should for some reason be unavailable. Some users, of course, would ordinarily use the electric connections, but when taking the instrument to such a distance away from the electrical connections that it would be inconvenient to employ this source of energy, the spring motor 45 will then be employed. In other instances, the spring motor will ordinarily be used, and the electric motor only employed when it is desired to keep the instrument running for some extended period, as for instance, when 50 a record is being played in connection with a repeater. Thus either driver may be regarded to be held ready to furnish assistance to the other, but from the fact that in the present illustration a commercial form of 55 spring motor and its governing mechanism is illustrated, the spring motor has been called a primary driver and the electric motor a subsidiary driver. The electric motor is shown mounted in a casing or housing 26 60 pivotally supported by the bracket 25 which

is secured to the under side of the table 1. The shaft 27 of the motor is shown extending above the table and there provided with a driving pulley 28. This pulley is preferably made of elastically yieldable material, as for instance, sponge rubber, and is preferably so proportioned that when the motor shaft is in substantially vertical position or parallel with the platen spindle 5, the driving pulley tractively engages the inner face 75 of the downwardly extending flange 29 of the record supporting platen. A leaf spring 30 is provided for pressing against the motor casing 26 and yieldably impelling the pulley 28 to its work. When the operator desires to employ the electric motor as the driver the casing is released to the influence of the spring 30. When, however, it is desired to employ the other driver and hold the electric motor in reserve, it is swung on its pivot 31. 80 The means illustrated for holding the driving means of this motor, namely, the pulley 28 out of engagement with the platen 2 of the rotatable member is shown in the form of a slide 32 provided with an upturned finger lug and a forked end 33 for straddling a lug 34 carried by the casing. By this means, the motor may be swung from its operative, namely, the illustrated position, to its inoperative position indicated by the dotted lines and held in this position by some suitable means, as for instance, a set screw 35 traversing the guide for the slide 32.

The current is supposed to be led into the motor by some suitable means, for instance, a cable 36. An automatic circuit breaker is located in the motor circuit, and is shown comprising a switch which is automatically capable of closing the circuit upon the commencement of rotation of the motor driven part and of opening the circuit upon the cessation of such rotation or upon the speed of rotation falling below a predetermined minimum. A pair of weights 37 are pivotally mounted on the motor shaft 27 and adapted to swing outwardly on a plane radially of the axis of rotation of the shaft on the attainment of proper speed. These weights will be readily seen to correspond to the weights of the balls of a ball governor. The weights are shown connected by an arch spring 38. This spring serves two functions, one of controlling the electric switch; the other of drawing the weights inwardly at the cessation of rotation against the action of which spring the weights expand. The motor is shown provided with a pair of brushes 39, 40 running upon a conventional form of commutator ring 41. A pair of posts 42, 43 are shown located adjacent the governing portion of the mechanism. These posts are shown carrying the contact or switch members 44, 45 in circuit respectively with the motor spindle 27 and the brushes 39, 40. In the illustration, the 95 100 105 110 115 120 125 130

switch member 44 is short relatively to the other member 45 which is of a resilient nature and extends across the crown of the arch 38. The parts are so proportioned that when the arch is in its normal or idle position, namely, the position illustrated in the drawings, it holds the switch member 45 out of engagement with the switch member 44, thereby maintaining the circuit open. 10 Whether or not the circuit will be closed upon a speed less than the maximum motor speed is governed and predetermined by the normal space between the contact points of the members 44 and 45. This space may be 15 so adjusted that the circuit will be closed during some predetermined ranges of speed, or so that it will be only closed during the maximum motor speed.

The closing of the circuit is effected by 20 the outward movement of the weights flattening the arch 38, whereupon the circuit is automatically closed. Further outward movement of the weights further flattens the arch to such an extent that there is no 25 frictional engagement between the arch spring and the switch member 45.

The circuit may be closed either by rotating the driven part of the platen 2, as for instance, by hand, or by means of a circuit closing device. There is shown a push button 46 connected with a pair of wires 47, 48 respectively connected to the switch members 44, 45. If it is desired to start the motor by means of the push button, this will 30 be depressed, thereby closing the circuit through the motor, immediately upon the motor attaining the proper speed to throw out the weights 37 and flatten the arch sufficiently, the points of the switch member 35 be depressed, thereby coming into engagement and establishing the circuit which is thereupon automatically maintained until the speed of the platen is reduced below the predetermined minimum. As is above stated this mechanism 40 44, 45 coming into engagement and establishing the circuit which is thereupon automatically maintained until the speed of the platen is reduced below the predetermined minimum. As is above stated this mechanism 45 is capable of use in many situations. For convenience it is shown in connection with a talking machine, and the following description of the operation is framed in the terms of such a machine. It is to be understood, however, that this is not to be construed as a limitation to the range of employment of the invention.

Certain mechanisms, particularly talking machines, are provided with automatic stops 50 for stopping the driven part upon completion of a given task, as for instance, in the talking machine upon the completion of the reproduction of the record. In the drawing, a commercial form of automatic brake is illustrated comprising a friction member 50 adapted to be moved into engagement with the inner face of the flange 29 of the platen. An extension spring 51 is provided for bringing the friction member 55 into operation at a predetermined time.

For the operation of this automatic brake, the sound horn 52 is shown provided with an arm 53 located in position to engage a tripping device 54 for the brake. The period in the cycle of platen rotation at 70 which the arm 53 engages the member 54 for tripping and releasing the brake is capable of being fixed at will so that the rotation of the platen will be stopped at a predetermined point on the record. 75

The operation of the illustrated mechanism is as follows: Assuming it is desired to reproduce a record employing a spring motor, the electric motor is moved to the dotted line position and there held by turning down the set screw 35, thus holding the driving pulley 28 out of engagement with the platen. The record disk 3 is placed in its proper position upon the platen 2, and the reproducing parts of the phonograph 80 properly adjusted, it being of course assumed that the spring within the spring barrel 8 is under proper tension. When the spring is thus under tension, this motor is thereby automatically clutched to the driver 90 part. The regulator 20 is then moved so that the friction member 18 is withdrawn from its engagement with the governor disk 17. The operator then gives the platen 2 a forward impulse by hand to assist the spring 95 of the motor in overcoming the inertia of the driven parts. The rotation of the platen then continues under the control of the governor mechanism operated through the spindle 5 in the manner above described. When 100 it is desired to rotate the platen and the record disk carried thereby by means of the electric motor, the spring motor is caused to run down, unless it has previously been permitted to do so. The driving portions 105 of the electric motor are then brought into driving engagement with the platen by unscrewing the set screw 35 and releasing the motor through the influence of its spring 30 as above stated elastically pressing the 110 driving pulley 28 against the inside of the flange 29. The record disk in some reproducing mechanism having first been properly adjusted the operator, as in the former case, releases the brake and gives the platen 115 a forward impulse by hand. Forward movement of driven part independently of the run down spring automatically unclutches the worm wheel 7 from the spring motor shaft 9. This rotation of the platen rotates the motor shaft 28, whereupon centrifugal force throws the weights 37 outwardly and flattens the arch 38 and permits the interengagement of the switch members 44, 45, whereupon the motor circuit is completed 120 and the motor continues to rotate the platen until this is stopped or its speed reduced sufficiently for the spring 88 to overcome the centrifugal force of the weights 37 and press the contact members 44, 45 apart. During 125 130

the rotation of the platen by either of the drivers, the governor mechanism connected with the platen through the spindle 5 is effective, excessive speed drawing the plate 17 against the friction applying means 18. In some instances, it may be desirable to start the platen by means of the electric motor without the manually applied forward impulse, in this case the motor circuit is closed 10 by the push button 46 and the circuit maintained closed until the automatic switch operating mechanism becomes effective. Upon the release of the push button 46, the circuit of the motor is then under the control of the 15 automatic switch operating mechanism.

When the driven mechanism is controlled with an automatic brake, as for instance, the brake 50 and its associated parts, the stopping of the driven part, the platen 2, by 20 means of this brake immediately stalls the motor which is accompanied by the inward movement of the switch governor weights 37 and the interruption of the motor circuit.

What I claim is:-

25 1. The combination with a talking machine comprising a record support, a spring motor for driving the support, a clutch mechanism between said spring motor and the support whereby the said support may 30 run forward independently of the said spring motor, and a governor for controlling the forward movement of the said support, of an electric motor permanently attached to the talking machine, means carried there- 35 by for engaging the said support and driving the same forward, and means operable at will for holding the electric motor idle or in driving relation with the record support.

2. The combination with a talking machine comprising a record turn-table disposed in a substantially horizontal position, a spring motor for driving the turn-table, a clutch mechanism between said spring motor and turn-table whereby the latter may 45 run forward independently of said spring, and a governor for controlling the forward movement of the said turn-table, of an independent motor comprising a supporting bracket secured to the talking machine, an 50 electric motor and casing pivotally supported by said bracket, the shaft of the motor extending upwardly, and a pulley mounted upon said shaft extension for engaging and frictionally driving the turn-table.

55 3. The combination with a talking machine comprising a record turn-table disposed in a substantially horizontal position, a spring motor for driving the turn-table,

a clutch mechanism between said spring motor and turn-table whereby the latter may 60 run forward independently of said spring, and a governor for controlling the forward movement of the said support, of an independent motor comprising a supporting bracket secured to the talking machine, an 65 electric motor and casing pivotally supported by said bracket, the shaft of the motor extending upwardly, a pulley mounted upon said shaft extension for engaging and frictionally driving the turn-table, and spring 70 means acting upon the said motor casing for impelling the pulley to its work.

4. The combination with a talking machine comprising a table disposed in a substantially horizontal position, a record support mounted above such table, a spring motor for controlling the support, a clutch mechanism between said spring motor and support whereby the said support may run forward independently of said spring, and 75 a governor for controlling the forward movement of the said support, of an independent motor comprising a supporting bracket secured to the under side of the table, an electric motor and casing pivotally supported 80 by said bracket, the shaft of the motor extending through the table, and a pulley mounted upon said shaft extension for engaging and frictionally driving the record support. 90

5. The combination with a record turn-table and a base plate, of a depending bracket secured to the base plate, a motor mounted on the bracket, a vertical power-shaft on the motor extending upwardly through the base plate, and a drive-wheel provided on the power-shaft and engaging the face of the record turn-table. 95

6. The combination, with a record turn-table having a depending annular flange and 100 a base-plate; of a depending bracket secured to the base-plate; a motor mounted on the bracket, a vertical power-shaft on the motor, extending upwardly through the base-plate and a drive-wheel provided on the power- 105 shaft and engaging the inner face of the depending annular flange of the record turn-table.

In witness whereof, I have hereunto signed my name in the presence of two subscribing 110 witnesses.

WILLIAM GENTRY SHELTON.
